US00D993426S

(12) **United States Design Patent** (10) Patent No.: **US D993,426 S**
(45) Date of Patent: **** Jul. 25, 2023**

(54) **BACK BRACE**

(71) Applicant: **G Force Braces LLC**, Manchester, NH (US)

(72) Inventors: **Douglas M. Goumas**, Bedford, NH (US); **Michael N. Bordieri, Jr.**, Katonah, NY (US); **Danielle N. Calvello**, Katonah, NY (US)

(73) Assignee: **G Force Braces, LLC**, Manchester, NH (US)

(**) Term: **15 Years**

(21) Appl. No.: **29/788,336**

(22) Filed: **May 5, 2021**

(51) LOC (14) Cl. **24-02**

(57) **CLAIM**

The ornamental design for a back brace, as shown and described.

DESCRIPTION

FIG. 1 is a front perspective view of a back brace showing the new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded view thereof;

FIG. 10 is a front perspective view of the back brace with both arms in a shortened position;

FIG. 11 is a rear perspective view with the back flap in an open position;

FIG. 12 is a front elevational view of the back brace in a fully extended position; and,

FIG. 13 is a rear elevational view of the back brace in a fully extended position.

The dot-dash broken lines in FIG. 9 show an order of assembly of the exploded view, and form no part of the claimed design.

1 Claim, 11 Drawing Sheets
